TOY BALL PROJECTOR AND CATCHER DEVICE

Duane W. Tressler, 507 Tradition Way, Mobile, Ala.

Filed July 7, 1961, Ser. No. 65,842

Term of patent 14 years

(Cl. D34—15)

FIGURE 1 is a side elevational view of a toy ball projector and catcher device showing my new design;

FIGURE 2 is a top plan view thereof;

FIGURE 3 is a bottom plan view thereof;

FIGURE 4 is a front elevational view thereof; and

FIGURE 5 is a rear elevational view thereof.

The ball shown in broken lines is for illustrative purposes only.

I claim:

The ornamental design for a toy ball projector and catcher device, as shown and described.
